UNITED STATES PATENT OFFICE.

MARY E. HUDSON, OF BUFFALO, NEW YORK.

SKIRT-MEASURE.

No. 800,580.

Specification of Letters Patent.

Patented Sept. 26, 1905.

Application filed June 10, 1905. Serial No. 264,602.

To all whom it may concern:

Be it known that I, MARY E. HUDSON, a citizen of the United States, residing at Buffalo, in the county of Erie and State of New York, 5 have invented certain new and useful Improvements in Skirt-Measures; and I do hereby declare the following to be a full, clear, and exact description of the invention, such as will enable others skilled in the art to which it applies to make and use the same, reference being had to the accompanying drawings, and 10 to figures of reference marked thereon, which form a part of this specification.

My invention relates to improvements in 15 skirt-measures which are employed to accurately determine the length of a skirt, or, in other words, to fix the uniform height of the entire lower edge of the skirt from the floor.

The object of my invention is to provide a 20 device of the character named which will combine simplicity of construction with ease and accuracy of adjustment and at the same time involve a minimum of cost in its production.

25 To these ends my invention consists of a metal base of extended dimensions provided with a vertical rectangular slot centrally arranged therein and extending entirely through such base and twin lugs on each side of the 30 rectangular slot, a vertical graduated standard removably secured between the lugs and in the rectangular slot, and a horizontal gaging or measuring arm adjustable vertically upon the graduated standard.

35 My invention further consists of certain details of construction, which will be fully hereinafter described and claimed.

In the drawings, Figure 1 is a side elevation 40 of my improved skirt-measure. Fig. 2 is an end elevation of the same with the base and lugs in central vertical section, and Fig. 3 is a top plan view of Fig. 1.

45 Referring to the drawings, 1 is the base, preferably of cast metal and of extended dimensions to give it the requisite stability.

2 is a vertical rectangular slot centrally arranged within the base and extending entirely through such base.

Upon the upper surface of the base 1 and 50 on each side of the slot 2 are the integral twin semicylindrical lugs 3 3, provided with screw-threaded sockets 4 4, adapted for the adjustable reception of the tightening-screws 5 5.

55 6 is a flat rectangular standard, preferably of wood, provided with vertical graduations 7 and a central longitudinal slot 8, extending

to within a short distance from each end of the standard 6. This standard 6 is removably secured in a vertical position in the slot 2 of the base 1 and between the lugs 3 3 by the 60 screws 5 5, which are forced tightly against the loose bearing-plates 9 9 on each side of the lower end of the standard 6.

10 is the horizontal gaging or measuring arm, preferably of wood, and adapted for 65 vertical adjustment along the standard 6 and graduated upon both upper and lower edges. Its inner end adjacent to the standard 6 is provided with the arched rectangular casing 11, which is in loose but snug slidable engagement with the graduated standard 6. The arched rectangular casing 11 is adapted to register with the semicircular lugs 3 3 in order to permit the horizontal gaging or measuring arm 10 to be brought into contact with 70 the base 1, or, in other words, as nearly in contact with the floor as possible. A screw-bolt 12 passes through the opposite side walls of the casing 11 and the elongated slot 8 in the standard 6, its projecting end being provided with the tightening thumb-nut 13, which 75 serves to hold the gaging or measuring arm 10 in any desired position upon the standard 6.

In assembling the parts the graduated standard 6, of any desired length, is inserted within the rectangular slot 2 until it rests upon the floor, its lower end being flush with the under surface of the base 1, as shown in Fig. 2. The metal bearing-plates 9 9 are then 80 slipped in on opposite sides of the standard 6 and the screws 5 5 adjusted into tight engagement with the bearing-plates, which serves to hold the standard 6 in rigid vertical position. The arched casing 11 is next slid down upon 85 the standard, the screw-bolt 12 passed through the side walls of the casing and through the longitudinal slot 8 in the standard 6, and the thumb-nut 13 screwed down upon the bolt 12 to secure the horizontal arm at any given 90 point upon the standard 6.

In operation the skirt-measure rests upon the floor and the person wearing the skirt to be operated on stands close to the horizontal arm 10, which has previously been adjusted 105 to the height at which the lower edge of the skirt is to hang from the floor. The skirt is marked at this point with chalk, and the person turns in successive positions until the entire skirt is marked at the height to which 110 it is to be finished.

It will be seen from the foregoing descrip-

tion that my improved device is extremely simple in its construction and arrangement of parts, its adjustment is quickly and easily made, and it is light and portable and occupies little space. The vertical standard herein shown is not more than one foot in height, as that length is sufficient to include the extreme highest and lowest points at which a skirt is to be marked. A longer standard may be quickly substituted for the one shown for use in defining the position of any trimmings which may be placed upon the skirt.

An important advantage which obtains with my improved construction is that the operator after adjusting the horizontal arm to its proper height is free to use both hands, one in holding the skirt against the horizontal arm and the other in manipulating the chalk.

I claim—

- 20 1. A skirt-measure consisting of a metal base of extended dimensions, provided with a vertical rectangular slot centrally arranged therein and extending entirely through such base and twin lugs on each side of the rectangular slot, a slotted vertical graduated standard removably secured between the lugs and in the rectangular slot, a horizontal gaging or measuring arm provided with a rectangular casing in sliding engagement with the stand-

ard, a bolt passing through the casing and 30 riding in the slot of the standard and a nut in engagement with the bolt for securing the casing and attached horizontal gaging or measuring arm at any fixed point on the vertical standard, all combined and operating 35 substantially as and for the purpose stated.

2. A skirt-measure consisting of a metal base of extended dimensions, provided with a vertical rectangular slot centrally arranged therein and extending entirely through such 40 base and twin semicylindrical lugs on each side of the rectangular slot, a vertical graduated standard removably secured between the lugs and in the rectangular slot and a horizontal gaging or measuring arm provided 45 with an arched rectangular casing in sliding adjustable engagement with the standard, the arched casing being adapted to register with the semicircular lugs, for the purpose stated, all combined and operating substantially as 50 shown and described.

In testimony whereof I have signed my name to this specification in the presence of two subscribing witnesses.

MARY E. HUDSON.
